DESIGN FOR A COMPACT

Enid Edson, New York, N. Y.

Application January 4, 1945, Serial No. 117,243

Term of patent 14 years

(Cl. D86—10)

To all whom it may concern:

Be it known that I, Enid Edson, a citizen of the United States, residing at 2 Beekman Place, in the city, county, and State of New York, have invented a new, original, and ornamental Design for a Compact, of which the following is a specification, reference being had to the accompanying drawing, forming part thereof. The dominant features of my design reside in the portions shown in full lines.

Figures 1 and 2 are top and bottom plan views respectively of a compact, showing my new design. Figure 3 is a side elevation of the compact shown in Figures 1 and 2.

I claim:

The ornamental design for a compact, substantially as shown and described.

ENID EDSON.
